J. R. CLAY.

LOCKING DEVICE FOR WINDOW SASHES.

APPLICATION FILED MAR. 25, 1920.

1,362,983.

Patented Dec. 21, 1920.

By his Attorney JAMES P. CLAY

Chas. C. Gill

UNITED STATES PATENT OFFICE.

JAMES R. CLAY, OF NEWARK, NEW JERSEY.

LOCKING DEVICE FOR WINDOW-SASHES.

1,362,983.

Specification of Letters Patent. Patented Dec. 21, 1920.

Application filed March 25, 1920. Serial No. 368,782.

To all whom it may concern:

Be it known that I, JAMES R. CLAY, a citizen of the United States, and a resident of Newark, in the county of Essex and State 5 of New Jersey, have invented certain new and useful Improvements in Locking Devices for Window-Sashes, of which the following is a specification.

The invention relates to means for locking 10 the upper and lower sashes of a window stationary either to prevent the rattling thereof or the opening of either sash from without.

My invention resides in a novel locking 15 device of wedge type to be removably entered between the face of one side of the lower sash and its retaining strip and having a pivoted or hinged member to be engaged with the adjacent face of the corresponding side of the upper sash, said wedge preventing the raising or rattling of the lower sash and said member preventing the lowering or rattling of the upper sash. The device of my invention serves both as a lock 20 to safeguard the window against intrusion from without and as means to prevent the usual rattling of window sashes by winds, and said device is equally effectual whether both sashes are entirely closed or both are partly open and also when one sash is wholly 25 closed and the other partly open. The pivoted or hinged member of the device is adjustable as to length so as to adapt the device to the varying separations of the vertical planes of the upper and lower sashes 30 of windows that may exist. I also preferably so construct my lock or catch that it is reversible and therefore adapted for application to either the right hand side or the 35 left hand side of a window sash.

The invention will be fully understood from the detailed description hereinafter presented, reference being had to the accompanying drawings, in which:

45 Figure 1 is a vertical transverse section, partly broken away, through a pair of window sashes and their casement equipped with the locking device of my invention, both sashes being shown in closed position and 50 the section being on the dotted line 1—1 of Fig. 2;

Fig. 2 is a horizontal section through the same taken on the dotted line 2—2 of Fig. 1;

Fig. 3 is a detached top view, partly in section, of my locking device; 55

Fig. 4 is a front elevation, partly in section, of the same;

Fig. 5 is a side elevation, partly broken away, of the same, and

Fig. 6 is a front elevation, partly in section, corresponding with Fig. 4, showing a modification in the construction of one detail of the device. 60

In the drawings 10 designates a portion of a window casement or framing of usual 65 or any suitable construction, 11 the lower window sash, 12 the upper window sash, 13 the usual sash cord for the lower sash, 14 the usual strip separating the sashes, and 15 the usual retaining strip for the lower sash, 70 all of said parts remaining unchanged so far as my invention is concerned.

My invention resides in a novel removable lock or catch to be applied to the window framing and sashes, and consists, in the 75 preferred construction, of a wedge-member 16 having a flat outer face 17, a pivoted or hinged link member 18, an adjustable sleeve 19 and a lock-nut 20 for binding the sleeve 19 in its adjusted positions. 80

The wedge member 16 has on its inner face the outwardly inclined diverging wedge faces 21, 22, at whose apex is secured or formed a bearing 23 for the link member 18. The wedge member 16 may be in one 85 integral piece, as shown, and the link member 18 is constructed from an integral rod fashioned to form a journal 24 to be mounted in the bearing 23 and two side arms 25, 26, which are substantially parallel and one 90 of which, 26, is longer than the other and screw-threaded to receive the sleeve 19, which is elongated in form and has an internally threaded bore to engage the threaded portion of said arm 26. The arm 25 is 95 made short so as to be free of the separating strip 14, as shown in Fig. 2, and when the device is positioned for use said arm is applied at the outer side of the sash cord 13, as shown. The arm 26 is bent or offset outwardly, as at 27, so that the side of the sleeve 19 may clear the separating strip 14 when the outer end of said sleeve is turned against the upper sash 12, as shown in Figs. 1 and 2. Upon the inner threaded portion of the 100 arm 26 is located the lock-nut 20, and this 105

nut is screwed against the inner end of the sleeve 19 in every adjustment of said sleeve for binding the sleeve rigidly in position. The sleeve 19 preferably has a ribbed outer surface, as shown, for convenience in rotating said sleeve by hand during the adjustment thereof on the arm 26.

In Figs. 1 and 2 I illustrate the lock as applied to the right hand side of a window, 10 and when so applied, the wedge surface 22 of the member 16 is pressed with firmness downwardly between the face of the right hand side of the lower sash 11 and its retaining strip 15, and the link member 18 is turned over toward the upper sash 12, the arm 25 being inserted back of the sash-cord 13 and the outer end of the sleeve 19 being wedged against the upper sash 12 so as to bind said sash firmly in position and against 15 rattling. The wedge member 16 serves to bind the lower sash 11 against rattling movement. If the combined length of the arm 26 and sleeve 19 should be so great as to prevent the same from acting as a prop wedging tightly against the upper sash 12, the 20 sleeve 19 must be adjusted inwardly on the arm 26 so as to decrease said length and permit the arm to stand at such angle that it may effectually bind the upper sash firmly 25 against its framing. After the device of my invention has been positioned, it will lock the lower sash against upward movement and the upper sash against downward movement and also prevent rattling movement of 30 both sashes.

Should it be desired to apply the lock to the left hand side of a window, the device will be turned over and applied as before, the wedge surface 21 then being forced downwardly between the lower sash and its adjacent retaining strip. Except for rendering the lock applicable for both the right and left hand sides of a window, the member 16 would only require one wedge surface instead of the two wedge surface shown, 40 and my invention would be present, in one form thereof, if only one wedge surface should be made use of. The sleeve 19 is employed so as to vary the length of the link member 18 to suit the conditions of spacing 45 between the vertical planes of the sashes of a window and to conveniently position the link member at such angle that it may bind against the upper sash as a prop and resist downward movement of said sash. The outer edge of the sleeve 19 is angular and this aids in such engagement thereof with the upper sash as to prevent downward movement of the sash, while not preventing upward movement thereof.

The bearing 23 may be formed from a piece of metal and secured to the member 16, as shown, or said bearing may be formed integrally with the wedge member, as shown 55 in Fig. 6, wherein, being a modification in

part, I number the wedge member 28 and the bearing 29, this bearing serving to receive the journal 24 and thereby pivotally connect the link member 18 with said wedge member.

The lock of my invention is composed of durable, easily manufactured, assembled and adjusted parts and may be handled as a unit.

What I claim as my invention and desire to secure by Letters-Patent, is—

1. A window sash lock of the character described, comprising a wedge member for insertion between the lower sash and its retaining strip, and a link member hinged to said wedge member adapted to serve as a prop against the upper sash.

2. A window sash lock of the character described, comprising a wedge member for insertion between the lower sash and its retaining strip, and a link member hinged to said wedge member adapted to serve as a prop against the upper sash and consisting of two arms of unequal length, the shorter of which is adapted to lie behind the sash cord and clear the separating strip between the sashes.

3. A window sash lock of the character described, comprising a wedge member for insertion between the lower sash and its retaining strip, and a link member hinged to said wedge member adapted to serve as a prop against the upper sash and being adjustable in length.

4. A window sash lock of the character described, comprising a wedge member for insertion between the lower sash and its retaining strip, and a link member hinged to said wedge member adapted to serve as a prop against the upper sash and comprising a threaded arm, an internally threaded sleeve adjustable thereon and a lock nut for securing said sleeve in its positions of adjustment.

5. A window sash lock of the character described, comprising a wedge member for insertion between the lower sash and its retaining strip, and a link member hinged to said wedge member adapted to serve as a prop against the upper sash and comprising a short arm to lie behind a sash cord and clear the sash separating strip of the window framing, a longer arm offset laterally to clear said strip and threaded on its outer portion, an internally threaded sleeve adjustable on said threaded portion of said longer arm and a lock nut for securing said sleeve in its positions of adjustment.

6. A window sash lock of the character described, comprising a wedge member having a flat face on one side and outwardly diverging wedge surfaces on the other side, and a link member hinged to said wedge member at a point between said wedge surfaces and adapted to serve as a prop against the upper sash while said wedge member

is held between the lower sash and its retaining strip.

7. A window sash lock of the character described, comprising a wedge member having a flat face on one side and outwardly diverging wedge surfaces on the other side, and a link member hinged to said wedge member at a point between said wedge surfaces and adapted to serve as a prop against the upper sash while said wedge member is

held between the lower sash and its retaining strip, and said link member comprising a threaded arm, an internally threaded sleeve adjustable thereon and means for locking said sleeve in its positions of adjustment. 15

Signed at New York city, in the county of New York and State of New York, this 24th day of March A. D. 1920.

JAMES R. CLAY.
